(57) CLAIM

I claim the ornamental design for tableware, as shown and described.

DESCRIPTION

FIG. 1 is a perspective view of tableware in accordance with the preferred embodiment of the present invention, showing my design;

FIG. 2 is a front view of the tableware shown in FIG. 1;
FIG. 3 is a rear view of the tableware shown in FIG. 1;
FIG. 4 is a left side view of the tableware shown in FIG. 1;
FIG. 5 is a right side view of the tableware shown in FIG. 1;

FIG. 6 is a top view of the tableware shown in FIG. 1;
FIG. 7 is a bottom view of the tableware shown in FIG. 1;
and,

FIG. 8 is another perspective view of the tableware of FIG. 1, wherein the tableware is spread butter and jam on the toast shown in FIG. 1.

The broken lines shown in the drawings are for the purpose of illustrating unclaimed portions of the tableware and form no part of the claimed design.
